SAFETY CONTROL SWITCH

Krell E. Spires, Jr., Dayton, Ohio, assignor to
 General Motors Corporation, Detroit, Mich., a
 corporation of Delaware

Application December 6, 1952, Serial No. 324,589

9 Claims. (Cl. 200—113)

1

This invention relates to a safety control switch for breaking the circuit to an electrically operated device in response to overload current demands of the device, such as a safety control switch for an electric motor.

An object of the invention is to provide a safety control switch having a thermally responsive mechanism responsive to current flow to an electrically operated device for opening an electric circuit to the device quickly in response to high overload conditions or current surge to the device and to open a circuit to the electrically operated device in a delayed manner in the event of a lesser prolonged overload current flow to the electrically operated device, the safety control switch thus having one quick acting release feature and another slow acting release feature which are effective dependent upon the type of current load carried by the electrically operated device.

Another object of the invention is to provide a safety control switch for breaking an electric circuit to an electrically operated device such as an electric motor, wherein there is provided a first thermally responsive bimetal member that is responsive to current flow to the electrically operated device for quickly releasing the safety control switch to break circuit to the electrically operated device on a sudden surge of current to the device, and which is provided with a second thermally responsive bimetal member that is thermally responsive from the first bimetal member to cause modification of the effect of the first bimetal member to delay release of the safety control switch as a result of prolonged overload to the electrically operated device resulting in a slow temperature increase of the primary bimetal member.

Another object of the invention is to provide a safety control switch responsive to current flow to an electrically operated device wherein a primary bimetal member is modified in its effective action by a secondary bimetal member in a manner to increase the trip time of the primary bimetal member upon effective actuation of the secondary bimetal member in response to temperature increase of the secondary bimetal member from the primary bimetal member.

Further objects and advantages of the present invention will be apparent from the following description, reference being made to the accompanying drawings wherein a preferred embodiment of the present invention is clearly shown.

In the drawings:

Fig. 1 is a cross sectional view of a safety control switch incorporating the feature of this invention;

2

Fig. 2 is a cross sectional view of a portion of the mechanism of Fig. 1, illustrating a normal position of the thermally responsive mechanism;

Fig. 3 is a cross sectional view similar to Fig. 2, but illustrating the positions of the primary and secondary bimetal members on a quick release of the control switch;

Fig. 4 is a cross sectional view similar to Figs. 2 and 3 but illustrating the positions of the primary and secondary bimetal members upon effective modification of the position of the primary member by the secondary member;

Fig. 5 is a cross sectional view similar to Figs. 2, 3 and 4, but illustrating the released position of the primary and secondary bimetal members effected from the modified position of the members as illustrated in Fig. 4;

Fig. 6 is a cross sectional view of a modified construction of the safety control switch.

When providing for breaking of an electric circuit the electrically operated device, such as electric motors, because of overloaded conditions on the electrically operated device, there are two independent conditions that must be considered and taken care of.

For example, there is one overload condition for an electric motor that results in a surge of electric current to the electric motor, such as a walled condition, or under extremely heavy overload. In this situation it is essential that the electric current be disconnected from the electric motor quickly to eliminate damage to the motor.

There is also a second type of overload condition caused in an electric motor, such as when the motor is operated under a medium overload condition, causing a current flow less than the high current surge required for quick release of the safety control switch to break control to the electric motor. This medium overload condition will result in a gradual temperature increase of the motor and the electric circuit must be broken to the electric motor within a reasonable time or damage will result to the motor.

However, if a safety control switch or thermal overload control, is initially set up for giving a quick response to a high current surge, the effective temperature increase of the bimetal member that actuates the device would result in the same kind of response in the event of a medium current overload, the initial deflection of the bimetal member depending entirely upon the temperature increase, which for sudden current surges is maintained at a relatively low volume.

However, an electric motor can operate satisfactorily under a medium overload condition for a relatively prolonged period of time, but if con-

tinued indefinitely, will result in damage to the motor. Thus, it is essential that the thermal overload control also be responsive to a gradual temperature increase of the motor resulting from a medium overload operating condition, but the response of the thermal overload control in breaking circuit to the electric motor should be over a much longer period of time and be ineffective until the motor has reached a dangerous operating temperature.

In this event, therefore, the safety control switch, or thermal overload control, is provided with one bimetal member that normally responds quickly to a high current surge to cause release of the overload mechanism and a second bimetal member is responsive to the temperature of the first bimetal member to cause a modified setting of the first bimetal member resulting in a delayed action of the first or primary member until the temperature rise resulting from the continued flow of overload current is sufficient to deflect the primary member for release of the thermal overload mechanism.

One form of the mechanism as illustrated in the drawings consists of a housing 10 constructed of insulating material and having a hollow interior 11. Contacts 12 and 13 are provided in series circuit with an electric motor 14, the contacts having a bridging element 15 for completing circuit through the electric motor in a manner hereinafter described.

The bridging member 15 is carried on an operating rod 16 journaled in walls 17 and 18 of the housing 10. The operating member carries a spring 19 that engages the bridging member 15 to push the same against the contacts 12 and 13 when the mechanism is in the position illustrated in Fig. 1. The operating member 16 is engaged by an actuating device 20, the operating member 16 extending through an opening in the actuating device 20 and having knife edges 21 and 21a that form a pivot connection between the operating member 16 and the actuating device 20.

The actuating device 20 is pivotally mounted on a pivot pin 22 secured to the wall 23 of the housing 10. A coil spring 24 has one end thereof engaging a stationary pin 25 and the other end thereof engaging the actuating member 20 to cause rotation of the member 20 in a clockwise direction about the pivot pin 22 when the member 20 is released by the primary bimetal member 30 in a manner hereinafter described.

The thermally responsive device for controlling the actuating member 20 comprises a primary bimetal 30 mounted on a boss 31 of the housing 10. The primary bimetal member 30 is carried upon a pin 32 and is thermally connected therewith to receive heat from a heating element 33 having one end thereof connected to the stud 34 and the opposite end to a connector 35. A connector 36 is engaged by the stud 34.

Thus, as can be seen in Fig. 1, electric current may be conducted through the electric motor 14 from the power line L1, through the contacts 12 and 13, thence through the connector 34, heating element 33, connector 35 to the power line L2.

The heating element 33 is thus responsive to current flow through the electric motor 14 and thus responsive to the load carried by the electric motor.

In normal operation, the bimetal member 30 is thermally sensitive to heat conducted to it through the stud 32 and is thus responsive to the current load through the electric motor 14. The bimetal member 30 will deflect downwardly, as

viewed in Fig. 1, to release the actuating device 20 and allow it clockwise rotation to move the operating member 16 in a leftward direction and break circuit through the electric motor by release of the bridging element 15 from the contacts 12 and 13.

To modify the action of the primary bimetal member 30 there is provided a secondary bimetal member 40 mounted upon the boss 31 and parallel to the primary bimetal member 30. The boss 31 of the housing 10 forms a heat insulating barrier between the bimetal member 30 and the bimetal member 40. However, the secondary bimetal member 40 is formed to engage primary bimetal member 30 at a point 41 as indicated in Fig. 1. The secondary bimetal member 40 bends in an upwardly direction as viewed in Fig. 1 to modify the action of the primary bimetal member 30.

To limit the modifying movement of the primary bimetal member 30 there is provided a stop member 45a that is carried on an arm 45 extending from the boss 31. The member 45 limits the upward movement of the primary bimetal member 30, and thus the degree of modification that can be effected for the secondary bimetal member irrespective of the maximum heat transfer to the secondary bimetal member.

In Fig. 2, the thermally responsive device, including the bimetal members 30 and 40, is illustrated in normal position. In this condition the bimetal member 30 has a slight tendency to move upwardly that is limited by engagement of the member 30 with the free end of the bimetal member 40. This position of the free end 46 of the bimetal member 30 relative to the free end 47 of the actuating device 20 is such that a small temperature rise of the bimetal member 30 will cause release of the actuating member 20 from the primary bimetal member 30, as illustrated in Fig. 3.

The aforesaid release of the actuating member 20 is that occasioned by a quick rise in temperature of the bimetal member 30 resulting from a high surge of current through the electric motor 14 representing a high overload condition or a walled condition.

At this time of operation of the primary bimetal member 30 on high overload condition of electric motor 14 causing quick release of the actuating device 20, the secondary bimetal member 40 will not be affected as its only thermal connection is through the bimetal member 30 and is insufficient to provide for flexing of the secondary bimetal member in the time of response of the primary member during the quick temperature rise of the primary bimetal member resulting from a high surge current through the heating element 33—33.

However, when the overload condition and the electric motor 14 is such that the current flow is insufficient to cause the initial temperature rise of the primary bimetal member 30 yet it is sufficient to result in a final temperature rise of the motor to cause such a prolonged overload condition it is essential that the primary bimetal member ultimately provide for release of the actuating device 20 to break circuit through the contacts 12 and 13.

To provide for such delayed action of the thermal overload and yet a positive action of the primary bimetal member 30, the secondary bimetal member 40 receiving its actuating heat through and from the primary bimetal member 30 will cause a resetting of the free end 46 of the primary bimetal member 30 relative to the free end 47 of the actuating device 20, as illus-

trated in Fig. 4. This repositioning results from upward deflection of the secondary bimetal member 40 as heated from the primary bimetal member 30. When the overload condition remains on the electric motor a sufficient period of time, the temperature of the primary bimetal member 30 will ultimately rise to a point at which the deflection of the bimetal member 30 is sufficient to release the actuating member 20 as illustrated in Fig. 5. The stop member 45 limits the maximum upward deflection of the bimetal member 30 and thus the maximum modification of the member 30 by the secondary bimetal member 40. After the secondary bimetal member 40 has caused modification of the setting of the primary bimetal member 30 by deflection of the bimetal member 40, as illustrated in Fig. 1, further heating of the bimetal member 40 will be ineffective for any further modification of the setting of the bimetal member 30 as limited by the stop member 45.

It will thus be seen that there is provided in one mechanism an arrangement for a quick release of the thermal overload control mechanism or a delayed action release of the control mechanism determined by the type of overload and the volume of the current drawn by the electric motor 14.

In Fig. 6, there is illustrated a slightly modified arrangement of the structure illustrated in Figs. 1 to 5, inclusive, wherein the primary bimetal member 300 is thermally sensitive to current load through the electric motor 14 resulting from the bimetal member 300 carrying the current. The structure in Fig. 6 is comparable to that heretofore described so that corresponding elements are given the same numbers as heretofore referred to, but with the suffix "a".

In the modification (Fig. 6) the primary bimetal member 300 is connected directly to the connector 36a at one end thereof and a flexible connection 301 is provided for connecting the opposite end of the bimetal member 300 to the connector 35a, thus being electrically in circuit with the electric motor 14.

While the embodiment of the present invention as herein disclosed, constitutes a preferred form, it is to be understood that other forms might be adopted, all coming within the scope of the claims which follow:

What is claimed is as follows:

1. In a safety control switch for breaking electric circuit to an electrically operated device in response to electric current flow to the device, the combination of, contact means for controlling flow of electric current to an electrically operated device, actuating means operably connected with said contact means and normally tending to be active to actuate the contact means to open electric circuit therethrough, and thermally responsive means operably connected with said actuating means to maintain the same normally inactive and thermally affected by the electric current flow to the electrically operated device to render said actuating means active to open said contacts, said thermally responsive means comprising a primary thermally responsive bimetal element connected with said actuating means normally detaining the same from actuation and directly releasing the same upon a temperature rise of the said primary element and a secondary thermally responsive bimetal element connected with and responsive to temperature rise of said primary element to modify the action of said primary element to delay release of said actuat-

ing means by the said primary element, said secondary bimetal element being thermally connected with said primary element in a manner to effect slow temperature response of said secondary element from said primary element whereby to effect modification of said primary element only during a slow temperature rise of said primary element as distinguished from a rapid temperature rise of said primary element resulting from a sudden surge of current to the electrically operated device.

2. In a safety switch for breaking electric circuit to an electrically operated device in response to electric current flow to the device, the combination of, contact means for controlling flow of electric current to an electrically operated device, actuating means operably connected with said contact means and normally tending to be active to actuate the contact means to open electric circuit therethrough, and thermally responsive means operably connected with said actuating means to maintain the same normally inactive and thermally affected by the electric current flow to the electrically operated device to render said actuating means active to open said contact means, said thermally responsive means comprising a primary thermally responsive bimetal element connected with said actuating means normally detaining the same from actuation and directly releasing the same upon a temperature rise of the said primary element and a secondary thermally responsive bimetal element connected with and responsive to temperature rise of said primary element to modify the action of said primary element to delay release of said actuating means by the said primary element, said secondary bimetal element being thermally connected with said primary element in a manner to effect slow temperature response of said secondary element from said primary element whereby to effect modification of said primary element only during a slow temperature rise of said primary element as distinguished from a rapid temperature rise of said primary element resulting from a sudden surge of current to the electrically operated device and a stop member engageable by said primary element to limit modification movement of said primary element by said secondary element relative to said actuating means.

3. In a safety control switch for breaking electric circuit to an electrically operated device in response to electric current flow to the device, the combination of, contact means for controlling flow of electric current to an electrically operated device, actuating means operably connected with said contact means and normally tending to be active to actuate the contact means to open electric circuit therethrough, and thermally responsive means operably connected with said actuating means to maintain the same normally inactive and thermally responsive to the electric current flow to the electrically operated device to render said actuating means active to open said contact means, said thermally responsive means comprising a primary thermally responsive bimetal element connected with said actuating means for normally detaining the same from actuation and thermally deflectable in one direction to directly releasing the same upon a temperature rise of the primary element and a secondary thermally responsive element connected with said primary bimetal element and thermally deflectable opposite to said primary element to modify the position of said primary element relative to said actuating means to delay release of

said actuating means by the said primary element, said secondary element being thermally connected with said primary element in a manner to effect slow temperature response of said secondary element from said primary element whereby to effect said position modification of said primary element only during a slow temperature rise of said primary element.

4. In a safety control switch for breaking electric circuit to an electrically operated device in response to electric current flow to the device, the combination of, contact means for controlling flow of electric current to an electrically operated device, actuating means operably connected with said contact means and normally tending to be active, actuating the contact means to open electric circuit therewith, and thermally responsive means operably connected with said actuating means to maintain the same normally inactive and thermally affected by the electric current flow to the electrically operated device to render said actuating means active to open said contact means, said thermally responsive means comprising a primary thermally responsive bimetal element temperature sensitive to current flow conducted therethrough to the electrically operated device and connected with said actuating means to normally detain the same from actuation and deflectable in response to the current conducted therethrough to release the said actuating means in response to a temperature rise of the said primary element effected by the current flow to the electrically operated device and a secondary thermally responsive bimetal element indirectly temperature-sensitive to the current flow through thermal connection with said primary element to modify the position of said primary element relative to said actuating means to delay release of said actuating means by the said primary element, said secondary element being thermally connected with said primary element in a manner to effect slow temperature response of said secondary element from said primary element whereby to effect said position modification of said primary element only during a slow temperature rise of said primary element as distinguished from a rapid temperature rise of said primary element resulting from a sudden surge of current to the electrically operated device.

5. In a safety control switch for breaking electric circuit to an electrically operated device in response to electric current flow to the device, the combination of contact means for controlling flow of electric current to an electrically operated device, actuating means operably connected with said contact means and normally tending to be active actuating the contact means to open electric circuit therethrough, and thermally responsive means operably connected with said actuating means to maintain the same normally inactive and thermally affected by the electric current flow to the electrically operated device to render said actuating means active to open said contact means, said thermally responsive means having a primary thermally responsive element deflectable in one direction upon a rise in temperature thereof and connected with said actuating means for normally detaining the same from actuation and for directly releasing the actuating means upon a temperature rise of said primary element and a secondary thermally responsive element deflectable in a direction opposite to that of said primary element upon a temperature rise in the same and connected with said primary element for temperature response

thereto to modify the action of said primary element by deflection of said secondary element in response to temperature rise thereof from said primary element to delay release of said actuating means by the said primary element, said secondary element being thermally connected with said primary element for slow temperature response of said secondary element relative to said primary element whereby to effect said modification of said primary element only during a slow temperature rise of said primary element as distinguished from a rapid temperature rise of said primary element resulting from a sudden surge of current to the electrically operated device.

6. In a safety control switch for breaking electric circuit to an electrically operated device in response to electric current flow to the device, the combination of, contact means for controlling flow of electric current to an electrically operated device, actuating means operably connected with said contact means and normally tending to be active, actuating the contact means to open electric circuit therethrough, and thermally responsive means operably connected with said actuating means to maintain the same normally inactive and thermally affected by the electric current flow to the electrically operated device to render said actuating means active to open said contact means, said thermally responsive means having a primary thermally responsive element deflectable in one direction upon a rise in temperature thereof and connected with said actuating means for normally detaining the same from actuation and for directly releasing the actuating means upon a temperature rise of said primary element and a secondary thermally responsive element deflectable in a direction opposite to that of said primary element upon a temperature rise in the same and connected with said primary element for temperature response thereto to modify the action of said primary element by deflection of said secondary element in response to temperature rise thereof from said primary element to delay release of said actuating means by the said primary element, said secondary element being thermally connected with said primary element for slow temperature response of said secondary element relative to said primary element whereby to effect said modification of said primary element only during a slow temperature rise of said primary element as distinguished from a rapid temperature rise of said primary element resulting from a sudden surge of current to the electrically operated device, and stop means engageable by said primary element to limit the modification movement of the said primary element irrespective of the temperature rise in said secondary element.

7. In a safety control switch for breaking electric circuit to an electrically operated device in response to electric current flow to the device, the combination of, contact means for controlling flow of electric current to an electrically operated device, actuating means operably connected with said contact means and normally tending to be active to actuate the contact means to open electric circuit therethrough, and thermally responsive means operably connected with said actuating means to maintain the same normally inactive and thermally affected by the electric current flow to the electrically operated device to render said actuating means active to open said contact means, said thermally responsive means comprising a primary temperature sensitive bimetal member thermally responsive to cur-

rent flow to the electrically operated device and engaging said actuating means for normally detaining the same from actuation and for directly releasing the same upon a temperature rise of said primary element, a secondary temperature sensitive bimetal member disposed adjacent said primary member and at least partially heat-insulated from the same but engaging the said primary member for temperature response therefrom said secondary member deflecting in a direction opposite to that of said primary member whereby to effect modification of the point of engagement of said primary member with said actuating means to delay release of said actuating means by said primary member, said secondary member having slow temperature response from said primary member whereby to affect said modification of said primary member only during a slow temperature rise of said primary member as distinguished from a rapid temperature rise of said primary member resulting from a sudden surge of current to the electrically operated device.

8. In a safety control switch for breaking electric circuit to an electrically operated device in response to electric current flow to the device, the combination of, contact means for controlling flow of electric current to an electrically operated device, actuating means operably connected with said contact means and normally tending to be active to actuate the contact means to open electric circuit therethrough, and thermally responsive means operably connected with said actuating means to maintain the same normally inactive and thermally affected by the electric current flow to the electrically operated device to render said actuating means active to open said contact means, said thermally responsive means comprising a primary temperature sensitive bimetal member thermally responsive to current flow to the electrically operated device and engaging said actuating means for normally detaining the same from actuation and for directly releasing the same upon a predetermined temperature rise of said primary element, a secondary temperature sensitive bimetal member disposed adjacent said primary member and temperature sensitive to said primary member for temperature response therefrom, said secondary member deflecting in a direction opposite to that of said primary member whereby to effect modification of the release of said actuating means by said primary member to a second and higher predetermined temperature, said primary member causing release of said actuating means on said first predetermined temperature rise completely independent of said secondary member, said secondary member causing said modifica-

tion of said primary member only during a slow temperature rise of said primary member as distinguished from a rapid temperature rise of the primary member resulting from a sudden surge of current to the electrically operated device.

9. In a safety control switch for breaking electric circuit to an electrically operated device in response to electric current flow to the device, the combination of, contact means for controlling flow of electric current to an electrically operated device, actuating means operably connected with said contact means and normally tending to be active to actuate the contact means to open electric circuit therethrough, and thermally responsive means operably connected with said actuating means to maintain the same normally inactive and thermally affected by the electric current flow to the electrically operated device to render said actuating means active to open said contact means, said thermally responsive means comprising a primary temperature sensitive bimetal member thermally responsive to current flow to the electrically operated device and engaging said actuating means for normally detaining the same from actuation and for directly releasing the same upon a predetermined temperature rise of said primary element, a secondary temperature sensitive bimetal member disposed adjacent said primary member and temperature sensitive to said primary member for temperature response therefrom, said secondary member deflecting in a direction opposite to that of said primary member whereby to effect modification of the release of said actuating means by said primary member to a second and higher predetermined temperature, said primary member causing release of said actuating means on said first predetermined temperature rise completely independent of said secondary member, said secondary member causing said modification of said primary member only during a slow temperature rise of said primary member as distinguished from a rapid temperature rise of the primary member resulting from a sudden surge of current to the electrically operated device, and stop means engageable by said primary member to limit the degree of modification thereof by said secondary member irrespective of the maximum temperature rise of said secondary member.
